(57) **CLAIM**

The ornamental design for an air quality monitoring device, as shown.

DESCRIPTION

FIG. 1 is a front left view of an air quality monitoring device in accordance with the design, showing the top, front and left sides thereof.

FIG. 2 is a rear left perspective view of the monitoring device of FIG. 1, showing the bottom, rear and left sides thereof.

FIG. 3 is a left side elevation view of the monitoring device of FIG. 1.

FIG. 4 is a right side elevation view of the monitoring device of FIG. 1.

FIG. 5 is a bottom plan view of the monitoring device of FIG. 1.

FIG. 6 is a top plan view of the monitoring device of FIG. 1.

FIG. 7 is a front elevation view of the monitoring device of FIG. 1.

FIG. 8 is a rear elevation view of the monitoring device of FIG. 1; and,

FIG. 9 is a front left perspective view of the monitoring device of FIG. 1, showing the top, front and left sides thereof and including environment.
